UNITED STATES PATENT OFFICE.

JOHN J. HAWXHURST AND EDWARD F. NICOLAI, OF NEW YORK, N. Y.

CARBURETING DEVICE.

1,078,349.

Specification of Letters Patent. Patented Nov. 11, 1913.

Application filed September 23, 1911. Serial No. 650,912.

To all whom it may concern:

Be it known that we, JOHN J. HAWXHURST and EDWARD F. NICOLAI, citizens of the United States, and residents of New York, 5 in the county of New York and State of New York, have invented certain new and useful Improvements in Multiple-Jet Carbureting Devices, of which the following is a specification.

10 The invention relates to devices for vaporizing liquid fuels and for effecting a suitable admixture of air therewith for use in internal combustion engines.

The invention relates more particularly to 15 carbureting devices of the multiple jet type; and it has for its object to provide a carbureting device of simple construction adapted to maintain an explosive mixture of uniform density and of ample quantity 20 under the various conditions met with in the operation of the internal combustion engine. A more efficient and satisfactory operation of the internal combustion engine is thus obtained and a considerable economy in 25 the use of the liquid fuel effected.

The nature of the invention will be best understood when described in connection with the accompanying drawings, in which—

Figure 1 is an end elevation of the im- 30 proved carbureting device. Fig. 2 is a longitudinal section taken on the line 2—2, Fig. 1. Fig. 3 is a fragmentary plan of the lower portion of the carburetor along the line 3—3, Fig. 2, and looking in the 35 direction of the arrows. Fig. 4 is a transverse section taken on the line 4—4, Fig. 3.

Similar characters of reference designate corresponding parts throughout the several views.

40 Referring now to Figs. 1 and 2 of the drawings, 10 designates a casing subdivided by a wall 11 to form a float chamber 12, within which is centrally located a primary carbureting chamber 21, and a secondary 45 carbureting chamber 13. An inlet pipe 14 communicates with the chamber 12 and is adapted to supply therethrough the liquid fuel, such as gasolene, from a suitable container (not shown). A needle valve 15

50 (Fig. 4) controls the inlet 14 through the operation of an annular float 16 which is adapted to engage the free end of a lever 17 pivotally connected to the casing 10 and whose other arm is connected with the valve 55 stem 18 of the needle valve. Thus, as gasolene fills the chamber 12, the float 16 therein

rises, and its top bearing against the free arm of lever 17, moves the same upwardly to close the passage-way 14. In thus controlling the valve 15 through a lever 17, danger of flooding the carburetor is considerably reduced as the said valve is operated through this expedient under a considerable force—much greater than that prevailing with carburetors in which the valve stem is actuated directly from the float. The weight of the float arm of lever 17 is made sufficient to slightly overbalance the needle valve 15 and insure the instantaneous opening of the valve as the float recedes.

70 About the casing 20 forming the carbureting chamber 21 is arranged the annular float 16, and within said chamber 21 is the primary carburetor jet 22 which communicates with the fuel chamber 12 through 75 a duct 23. Chamber 21 communicates with an air cage 25 to admit air about the jet 22, the said air cage being normally closed by a valve piece 26 whose outer face is preferably somewhat concaved, as shown, to reduce hissing during admission of the air. This valve piece is mounted loosely on an adjustable spindle 27 and is held against a seat 28 of the cage by means of a spring 29 mounted about the spindle. A portion of 85 this spring is preferably made cylindrical and the remainder conical, to provide through the latter portion a lighter tension during the first period of the opening of the valve, which tension increases as the 90 valve continues to be opened. The tension of the spring may be varied by turning spindle 27 which is threaded at its outer end, and is provided with a shoulder 30 against which one end of the spring 29 95 bears, the other bearing against the valve piece 26. The chamber 13 of the secondary carburetor is likewise provided with a jet 31 opening into an outlet 32, the said chamber being in free communication at the bottom with the outside atmosphere, and the said jet 31 communicating with the gasolene chamber 12 through a duct 34. This duct is controlled by an adjustable needle valve 35 which is set to permit the maximum flow 105 of gasolene desired. The height of jet 31 is somewhat greater than that of the jet 22 to prevent overflow through same when the carburetor is at an angle.

110 To the lower casing 10 is arranged to be secured an upper casing 40, providing upper chambers 41 and 42 and an outlet cham-

ber 43, the latter chamber being adapted to be connected to the intake pipe (not shown) of an internal combustion engine. Chamber 41 is in direct communication with the chamber 21; and chamber 42 with the outlet 32 of chamber 13. A normally closed valve 44 closes the passage-way 45 between chambers 41 and 43, the same being under a suitable tension afforded by a spring 46 bearing 10 against the outer end of said valve piece 44 and a valve seat 47 at the opposite end of said chamber 43. Valve stem 48 of the valve piece 44 extends through the casing 40, and its end is connected with a suitable 15 operating lever 49, whereby the passage-way 45 may be throttled as desired. A by-pass 50, however, is provided around valve 44 to admit sufficient of the gaseous mixture to chamber 43 to enable the engine to run 20 free; and, usually, also to enable the engine to be started without necessitating the opening of valve 44 which would tend to cause the engine to race. The effective area of this by-pass may be adjusted by means of 25 a screw 51 passing through the casing into said by-pass.

The chamber 42 is provided with an auxiliary air inlet valve 60, mounted about a sleeve 61 secured to the casing, and provided 30 at its inner end with a shoulder 62 between which and the said valve piece 60 is held a spring 63, preferably conical, to provide the necessary tension on the said valve piece. The outer face of this valve piece 35 is concaved to reduce the hissing caused by the air entering through the valve; and, for a similar reason, a lip 74 is arranged to project from valve cage of casing 40. The tension of the spring may 40 be varied by turning the sleeve 61 whose outer end is screwed into and passes through the casing 40. The chamber 42 is, furthermore, provided with a plurality of superimposed outlet valves 64, 65, and 66, the latter 45 seating against the valve seat 47 and being provided with a passage-way 67 which is normally closed by the valve piece 65. This valve piece in turn is provided with a passage-way 68 normally closed by the valve 50 piece 64. A valve stem 69 extends from valve piece 64 through the valve pieces 65 and 66 and the valve seat 47, the said valve pieces 65 and 66 being provided with respective sleeves 70 and 71 fitting over the said stem 55 69. The stem 69 terminates within chamber 43 at a predetermined distance from the outer face of the valve 44, the sleeve 70 somewhat farther from the said valve seat 44, and the sleeve 71 still farther. With 60 this arrangement, as the stem 48 is forced inwardly through the lever 49, valve 44 is first opened; and then, successively, the valve 64 through the face of valve 44 making contact with the stem 69, then the 65 valve 65 through sleeve 70, and finally also

the valve 66 through its sleeve 71. In this manner, constantly increasing areas of opening for the outlet of the gaseous mixture, first from the primary carburetor 12, and then from the secondary carburetor 13, are provided to the outlet chamber 43. The valve stem 48 is constantly under the tension produced by spring 46; but when the valve pieces 64, 65, 66 are open, the tension on stem 48 is increased by that of a spring 72. This spring is mounted within the outer end of sleeve 61 and bears against a plunger 73 supported in the said sleeve 61 and arranged to bear against the valve 64 to maintain the said valves 64, 65 and 66 normally in closed position.

With the multiple jet carburetor herein set forth it will be understood that priming of the carburetor is quite unnecessary for the area of outlet of the primary carburetor may be made sufficiently small to establish a proper starting mixture, the secondary carburetor providing the additional gaseous mixture as required. The two carburetors may operate quite independently of each other as well as in combination.

A considerable economy of space, as well as of fuel, is effected by this carburetor. The vaporized liquid is drawn through and around the various valves in such a manner as to be thoroughly mixed with the proper proportion of air drawn into the carburetor, and provides a highly efficient mixture at all speeds desired, the quantity supplied being controlled as hereinbefore set forth.

We claim:

1. A multiple jet carbureting device, comprising: a plurality of casings provided with suitable inlets and outlets and forming independent carbureting chambers; a fuel jet in each of said chambers; means to supply liquid fuel thereto; means to admit air to the respective carburetors; means controlling the outlets from the respective carburetors, one of said means including a plurality of controlling members adapted to successively present new areas of outlet; and actuating means for said controlling means, the actuating means for the respective controlling means being normally independent of each other and one of the same being adapted to first operate one of said controlling means a predetermined amount and thereupon to engage the other of said actuating means to successively open the corresponding outlets.

2. A multiple jet carbureting device, comprising: a plurality of casings provided with suitable inlets and outlets and forming independent carbureting chambers; a fuel jet in each of said chambers; means to supply liquid fuel thereto; means to admit air to the respective carburetors; means to admit an additional supply of air to one of said carburetors as required; means control-

ling the outlets from the respective carbureters, one of said means including a plurality of controlling members adapted to successively present new areas of outlet; 5 and actuating means for the respective controlling means, the actuating means for the respective controlling means being normally independent of each other and one of the same being adapted to first operate one 10 of said controlling means a predetermined amount and thereupon to engage the other of said actuating means to successively open the corresponding outlets.

3. A multiple jet carbureting device, comprising: a plurality of casings provided with suitable inlets and outlets and forming independent carbureting chambers; a fuel jet in each of said chambers; means to supply liquid fuel thereto; means to admit air 20 to the respective carbureters; means controlling the outlets from the respective carbureters, one of said means including a plurality of controlling members adapted to successively present new areas of outlet; and 25 actuating means for said controlling means, the actuating means for the respective controlling means being normally independent of each other and the first of the same being adapted to first operate the corresponding 30 controlling means a predetermined amount and thereupon to engage the other of said actuating means to successively operate the plurality of controlling members.

4. A carbureting device comprising: a plurality of casings providing a primary carbureting chamber and a secondary carbureting chamber independent thereof, the respective chambers being provided with suitable inlets and outlets; a fuel jet in each 40 of said chambers; a float chamber to supply liquid fuel to said primary jet and chamber, and means affording communication between said float chamber and the said secondary jet and carbureter; means to admit air about the respective jets; means to admit air above said secondary jet; a valve

controlling the flow of gaseous mixture from the primary carbureter; a plurality of valves controlling the flow of gaseous mixture from the secondary carbureter to 50 provide a successively increasing area of outlet from the same; means to open said primary carbureter valve; and means connected with said secondary carbureter valves adapted to be successively engaged by the 55 said primary carbureter valve when the same is opened a predetermined amount.

5. A carbureting device comprising: a plurality of casings containing a primary carbureting device and a secondary carbureting device independent thereof and adapted to discharge into a common outlet; and means controlling the discharge from said carbureting devices into the common outlet, including a valve controlling the discharge from the primary carbureting device; a plurality of superimposed valves controlling the discharge from said secondary carbureting device; all of said controlling valves lying in the same longitudinal axis; a stem extending from the outermost valve of said secondary carbureter valves and terminating at a predetermined distance from said primary carbureter valve to be engaged thereby when the same is moved toward said stem; sleeves extending from the other of said plurality of valves, surrounding said stem and terminating successively at predetermined distances from the end of said stem to be engaged upon the further movement of the primary carbureting valve toward the said stem; and resilient means acting against said plurality of valves.

Signed at New York, in the county of 85 New York, and State of New York, this 20th day of September A. D. 1911.
